LIQUID SPRAYER

Lester C. McKay, Elmwood Park, Ill., assignor to
Sears, Roebuck and Co., Chicago, Ill., a corpora-
tion of New York

Application March 31, 1941, Serial No. 386,017

9 Claims. (Cl. 299—89)

This invention relates to liquid sprayers and is concerned more particularly with paint and other sprayers including those of the gun type carried and moved by the operator's hand, usually with a rubber or other flexible tube connection to a relatively stationary air compressor or tank containing air under pressure.

The conventional paint gun of the type referred to has been found unsatisfactory because the arrangement of its parts requires the operating hand and wrist of the user to assume awkward, unnatural and inconvenient positions relative to his arm in order to hold the nozzle in the proper position in service, with the result that the operator's wrist and arm become so fatigued that he cannot operate the gun for more than a minute or so continuously, with a consequent impairment in his efficiency and the quality of work done, and loss of time to accomplish a given assignment.

It is accordingly an object of my invention to provide a gun of the type referred to having the advantages of conventional guns and none of the above-mentioned disadvantages.

A further object is to provide a gun so balanced that its nozzle may be held with complete comfort and minimum fatigue in proper juxtaposition to the surface of to be treated, irrespective of the volume of the contents of the can and irrespective of the direction in which the nozzle points.

It is also an object of my invention to provide a paint gun in which the handle also functions as the connection between the nozzle and the paint can carried therewith.

Another object is to provide a gun of the type referred to formed to be used interchangeably with a can to be carried therewith or with a hose leading from a stationary source of liquid supply.

An additional object is to provide a gun having the advantages referred to using a conventional supply can.

Further objects and advantages of my invention will appear as the description proceeds.

The word "paint" is used herein not by way of limitation but for convenience to obviate the necessity of using the term "treating liquid."

The invention will be better understood upon reference to the following description and accompanying drawings, in which:

Fig. 1 is a longitudinal view, mostly in section, some of the parts being in different planes, through a gun embodying features of my invention, showing the air and paint conduits and taken as indicated by the line 1—1 in Fig. 2.

Fig. 2 is a fragmentary front sectional view taken as indicated by the line 2—2 in Fig. 1.

Fig. 3 is a front sectional view taken as indicated by the line 3—3 in Fig. 1.

Fig. 4 is a sectional view looking down, taken as indicated by the line 4—4 in Fig. 1, the paint tube connection being omitted.

Fig. 5 is a fragmentary view similar to Fig. 1, partly in section and partly in elevation, showing the paint conduits, some of the parts being in different planes, taken generally as indicated by the line 5—5 in Fig. 2.

Fig. 6 is a fragmentary bottom sectional view taken as indicated by the line 6—6 in Fig. 1.

Fig. 7 is a sectional view looking upward and taken as indicated by the line 7—7 in Fig. 1.

Fig. 8 is a fragmentary sectional view looking upward and taken as indicated by the line 8—8 in Fig. 1.

Fig. 9 is a side elevation of the structure shown in Fig. 1.

Fig. 10 is a top plan view of the device, taken as indicated by the line 10—10 in Fig. 9.

Fig. 11 is a fragmentary section-elevation similar to the portion projecting down into the can in Fig. 1 but modified for connection with a hose from a stationary paint supply.

Referring more particularly to the drawings, I have shown in Figs. 1—10 an embodiment of my invention in which a paint can is connected with the nozzle as a portable unit.

In this form of the invention, there is provided a nozzle body 15 and a handle 17 therefor preferably cast integral and preferably with their axes in substantially the same plane, the handle being contoured to fit comfortably in the hand, and forming preferably an obtuse angle with the forepart 19 of the nozzle body, the angle being selected with an eye to permitting the hand and

wrist to be held in natural, unstrained positions relative to each other and the operator's arm when the device is normally in use. This angle accordingly is preferably about 100°. A paint can 21 detachably carried by the handle completes the assembly which is carried as a unit in the hand of the operator.

The handle 17 has preferably in the lower part thereof a lateral bore 23 tapped at its outer end 25 for connection to a compressed air supply hose 27 at a point below the hand on the handle. The other end of said bore meets a longitudinal passage 29 whose free lower end is closed as by a cleanout plug 31 engaging a gasket 33 and whose upper end meets the inner end of a bore 35 which extends preferably longitudinally

of the nozzle body 15. The free end of the bore 35 is closed as by a cleanout plug 37 which adjustably carries an air control adjusting stop screw 39 hereinafter referred to.

A short smaller bore 41 forming an inner extension of the bore 35 is adapted to be yieldably closed against communication with the passage 29 by a valve element 43 engageable with the shoulder or seat 45 between the bores 35 and 41. The valve element is detachably mounted as by 10 means of a screw 47 on the end 49 of a valve stem 51, said end being of smaller diameter than the bore 41 to afford an annular passage 53 therebetween. The stem 51 has an enlarged portion 55 slidably fitting the bore 41 and providing therewith suitable bearing to properly guide the stem in its reciprocations. A packing gland 57 is fitted about the enlarged portion 55 of the stem 51 and in a counterbore 59 at the front end of the bore 41. The enlarged portion 55 of the stem has a flange 61 between which and the gland 57 a coil spring 63 is disposed under an initial compression to insure the closing of the valve element 43 when opening pressure thereon is not applied by the operator.

A trigger 65 preferably of stamped sheet metal or other material, and having yoke arms 67 hinged as at 69 to the nozzle body 15, has an actuating portion slotted as at 71 and straddling a forward portion 73 of the stem beyond the flange 61 of the stem. The tongue or hook 75 of the trigger extends downwardly preferably in front of and normally spaced from the upper part 71 of the handle, where the hook is conveniently pulled by the operator's forefinger A, second finger or both. The stem 51 has a flange 79 which cooperates with the flange 61 in retaining the trigger 65 in properly assembled relation to the stem.

The nozzle body 15 has an open recess 81 accommodating the gland 57, spring 63, flanges 61 and 79 and trigger 65.

Extending upward from the bore 41 is a port 83 which terminates in another longitudinal bore 85 in the nozzle body 15, the rear end of the bore 85 being closed as by a cleanout plug 87. The bore 85 terminates forwardly short of the forward end of the nozzle body 15 and communicates with the front of said body by means of a passage 89. The passage 89 leads to a circular cavity 91 in the front of the nozzle body.

A member 93 hereinafter referred to in more detail is detachably mounted as by a snug fit in the cavity 91 at the front of the nozzle body so as to give said cavity an annular shape. Fitted about the member 93 is a jet member 95 abutting the front of the nozzle body and having a flange 97 with which a flange on a nut 99 engages, the nut being threaded at 101 on the nozzle body to maintain said jet member in leakproof engagement with the nozzle body. The member 93 is exteriorly fluted at 103 and is spaced from the front of the jet member 95 as shown at 105 so that clear passage is provided from the bore 89 to the annular space 91, forward through the flutes 103 into the space 105 and through the jet opening 107 to the outside.

From the foregoing, it is apparent that air under pressure introduced at 23 will follow the arrows 109 up the passage 29 and, when the valve 43 is open, enter the annular passage 41, continue through the port 83 into the bore 85 and continue through the bore 89, annular passage 91, flutes 103, space 105 and opening 107 to the outside.

A continuation of the port 83 is shown at 111

extending down from the bore 41 and terminating at the upper end of a bore 113 which may extend alongside the bore 29 in the handle 17, the bore 113 terminating at the lower end of the handle. The handle 17 has a flange 115 adjacent the lower end thereof. Below and in engagement with the flange 115 is a gasket 117 in turn engaged by an adapter 119 having an inwardly extending flange 121 disposed about a lower threaded sleeve 123 extending from the handle 17. A nut 125 is threaded on the sleeve 123 and engages a gasket 127 contacting the underside of the flange 121. Thus, when the nut 125 is tightened on the sleeve 123, the adapter 119 is sealed and secured to the handle. The adapter 119 is internally threaded at 129 to receive the threaded neck 131 of the paint can 21, said neck terminating in an inwardly directed flange 133 engaging a gasket 135 which seats against a shoulder 137 on the adapter to provide a leakproof connection. The sides of the nut 125 are spaced from the adapter 119, gasket 135 and paint can neck 131 to provide clearance as shown at 139. The adapter has a recess 141 communicating with the bore 113 in the handle, and a port 143 which establishes communication between the recess 141 and the space 139 and consequently with the interior of the can above the level 145 of the paint 147.

A needle valve 149 controls the flow from the port 111 to the passage 113 in the handle. Accordingly, when the valve 43 is open, admitting air from the handle passage 29 to the bore 41, the needle valve 149 may be adjusted to vary the air pressure on the paint 147 in the can 21.

The handle 17 has another longitudinal bore 151 which terminates downwardly in the sleeve 123. Said sleeve is interiorly threaded and threadedly receives a collar 153 to which is secured a tube 155 extending upward substantially throughout the length of the bore 151 and having its opposite end 157 secured in a reduced bore 159 extending from the upper part of the bore 151. A further reduced bore 161 extends from the bore 159 and terminates at its upper end 163 in a transversely disposed passage 165 (Figs. 1 and 5) extending longitudinally in the nozzle body 15. The rear end of the passage 165 is closed as by a cleanout plug 167. The passage 165 terminates forwardly short of the front of the body 15. The forepart 19 of the body member 15 has a longitudinal bore 169 which communicates with the passage 165 by means of a lateral channel 171, the outer end of which is suitably closed as by a plug 173. The valve member 93 (Fig. 1) has a sleeve extension 175 securely fitted in the forward end of the bore 169 and, in advance of the sleeve 175, has a tapered forwardly converging seat 177 terminating immediately behind the rear end of the jet passage 107 in the jet member 95.

Threaded in the bore 169 in the nozzle body 15 is a packing gland adapter 179 in which a packing gland 180 is threaded. A forward extension 181 passes through the gland 180 and has a forwardly converging tapered end 183 adapted to be yieldably held in snugly fitting contact with the valve seat 177 by the spring 63.

Secured fluid tight to the nut 125 is a flexible tube 189 whose lower end is embedded in a lead or other weight 191 of spherical or other suitable shape, adapted to rest on the bottom 193 of the can 21 in such a manner as to at all times hold the open end 195 of the tube 189 adjacent and free from said bottom for the entrance of paint,

the flexibility of the tube permitting the weight to move to the lower part of the can regardless of the position of the can, to insure constant supply of paint even when the nozzle body is vertical.

It has been explained how, in response to a pull on the trigger 65, air finds its way to the jet opening 107 and, under the control of the needle valve 149, such air also finds its way to the upper part of the can 21 to exert pressure on the paint 147. The pull on the trigger 65 also draws the tapered valve element 183 off the associated seat 177, whereupon the air pressure over the paint 147 is effective to force the paint to enter the mouth 185 of the tube 183 and pass along said tube and into the sleeve 183 and pipe 185, the passage 183, port 171, bore 169, and sleeve 173 through the jet opening 107. As the paint under pressure issues from the valve seat 177, it mingles with the air under pressure in the space 105, producing a thoroughly mixed and atomized paint spray in and beyond the jet opening 107.

A trigger guard 197 extending forwardly from the handle 17 is so located as to be engaged with the upper side of the third finger of the hand embracing the handle. When the hand thus embraces the handle, the center of gravity of the entire appliance including the paint can 21 and its contents extends substantially in a plumb line passing approximately through the point B, so that when the operator is using the appliance with a horizontal jet, i. e., with the axis of the nozzle body 15 substantially horizontal, it is not necessary for him to hold his hand and wrist in an unnatural position or exert upward force at the wrist and hand to maintain the nozzle body in the proper position for such service.

The distribution of weight is such, moreover, that the appliance is balanced approximately in the vicinity of the point B, regardless whether the can 21 is substantially full or nearly depleted.

In the embodiment of the invention chosen for illustration, the nozzle body 15 simulates generally the streamline shape of a bullet. To carry out that motif, I have provided a cap 199 which has near its rim an inwardly projecting rib 201 which is adapted to snap over the rear end 203 of the nozzle body and into a circumferential groove 205 in said end. Said end of the nozzle body is provided with a generally longitudinally extending recess 207 extending forward from the groove 205 and providing an entrance for a screw driver or other tool to facilitate attachment of the cap. Said cap, when in place, conceals the plug 37, pin 39 and plugs 87 and 167 at the rear end of the nozzle body.

The appliance is preferably provided with a hook 209 by means of which the appliance may be suspended from any suitable fixed part when not in use.

In the event it is desired to use the nozzle in connection with a stationary paint tank, the adapter 119 and tank 21 would be dispensed with and the nut 125 and associated tube 189 and the weight 191 would be replaced by a hose coupling nut 211 carrying a hose coupling 213 projecting downwardly from the nut to receive a hose 215 which may extend to the stationary paint tank (not shown).

Various modifications may suggest themselves to those skilled in the art without departing from the spirit of my invention and, hence, I do not wish to be restricted to the specific form shown 75

or uses mentioned, except to the extent indicated in the appended claims.

I claim:

1. A paint gun comprising a paint can, a handle extending upwardly and forwardly from said can when said can rests on a horizontal support, means connecting said handle to said can, and a nozzle body connected to an upper part of said handle and extending forwardly therefrom in a substantially horizontal plane when said can is resting on the support, the weight of the parts being so distributed that when the handle is in the grasp of the operator's hand, said body tends by gravity to assume a substantially horizontal position.
2. A paint gun comprising a nozzle body, a handle depending from an intermediate portion of said body, the juncture of the rear part of said handle with said body being shaped to fit naturally with the part of the hand between the thumb and forefinger, trigger-controlled valve means for said nozzle body, said trigger being arranged to be operated conveniently by a finger of the hand grasping said handle, a guard carried by said handle below said trigger and adapted to rest on the third finger of the hand, and a paint can connected to the lower end of said handle, the distribution of weight of the parts being such that the center of gravity is disposed adjacent said guard.
3. A paint gun comprising a nozzle, a handle inclined downwardly and rearwardly from said nozzle when said nozzle is substantially horizontal, a paint receptacle connected to the lower part of said handle with the major part of said receptacle disposed forwardly of said lower part of said handle, said nozzle extending from said handle in the same direction in which said major part of said receptacle is disposed in relation to said handle, the distribution of the weight of the gun being such that the center of gravity of the gun is substantially intermediate the ends of said handle.
4. A paint gun comprising a nozzle, a handle depending from said nozzle when said nozzle is substantially horizontal, a paint receptacle connected to the lower part of said handle with the major part of said receptacle disposed forwardly of said lower part of said handle, said nozzle extending from said handle in the same direction in which said major part of said receptacle is disposed in relation to said handle, the distribution of the weight of the gun being such that the center of gravity of the gun is substantially intermediate the ends of said handle, and means detachably coupling said handle with said receptacle, said means including a receptacle cap having its outer surface configured to merge with and form a smooth substantially uninterrupted continuation of the adjacent outer surfaces of said receptacle and handle.
5. A paint gun comprising a nozzle, a handle depending from said nozzle when said nozzle is substantially horizontal, a paint receptacle connected to the lower part of said handle with the major part of said receptacle disposed forwardly of said lower part of said handle, said nozzle extending from said handle in the same direction in which said major part of said receptacle is disposed in relation to said handle, the distribution of the weight of the gun being such that the center of gravity of the gun is substantially intermediate the ends of said handle, and means detachably coupling said handle with said receptacle.

tacle, said means including a receptacle cap having its outer surface configured to merge with and form a smooth substantially uninterrupted continuation of the adjacent outer surfaces of said receptacle and handle, the remainder of said coupling means being disposed within the confines of said surfaces.

6. A paint gun comprising a nozzle, a paint receptacle, a handle depending from said nozzle to said receptacle when said nozzle is substantially horizontal, the axis of said handle at the juncture thereof with said receptacle being eccentric to the axis of said receptacle, said nozzle extending from said handle in the same direction in which the axis of said receptacle is disposed in relation to the axis of said handle, and means detachably coupling said handle with said receptacle, said means including a receptacle cap having its outer surface configured to merge with and form a smooth substantially uninterrupted continuation of the adjacent outer surfaces of said receptacle and handle.

7. A paint gun comprising a nozzle, a paint receptacle, a handle depending from said nozzle to said receptacle when said nozzle is substantially horizontal, the axis of said handle at the juncture thereof with said receptacle being eccentric to the axis of said receptacle, said nozzle extending from said handle in the same direction in which the axis of said receptacle is disposed in relation to the axis of said handle, and means detachably coupling said handle with said receptacle, said means including a receptacle cap having its outer surface configured to merge with and form a smooth substantially uninterrupted continuation of the adjacent outer surfaces of said receptacle and handle, the remainder of said coupling means being disposed within the confines of said surfaces.

8. A paint gun comprising a nozzle, a handle depending from said nozzle when said nozzle is

substantially horizontal, a paint receptacle connected to the lower part of said handle with the major part of said receptacle disposed forwardly of said lower part of said handle, said nozzle extending from said handle in the same direction in which said major part of said receptacle is disposed in relation to said handle, a cap having a threaded connection with said receptacle and an adjustable connection with said handle, whereby said cap and handle may be adjusted to locate said receptacle in the aforesaid relation whenever the parts are assembled, and means for maintaining said cap and handle in the desired adjustment, said handle having a paint passage leading to said nozzle, and said cap having an opening affording access of paint from said receptacle to said passage.

9. A paint gun comprising a nozzle, a handle depending from said nozzle when said nozzle is substantially horizontal, a paint receptacle connected to the lower part of said handle with the major part of said receptacle disposed forwardly of said lower part of said handle, said nozzle extending from said handle in the same direction in which said major part of said receptacle is disposed in relation to said handle, a cap having a threaded connection with said receptacle and an adjustable connection with said handle, whereby said cap and handle may be adjusted to locate said receptacle in the aforesaid relation whenever the parts are assembled, and means for maintaining said cap and handle in the desired adjustment, said handle having a paint passage leading to said nozzle, and said cap having an opening affording access of paint from said receptacle to said passage, said cap having its outer surface configured to merge with and form a smooth substantially uninterrupted continuation of the adjacent outer surfaces of said receptacle and handle.

LESTER C. MCKAY.
